UNITED STATES PATENT OFFICE.

HENRY L. GRASMUK, OF NEWARK, NEW JERSEY, ASSIGNOR TO KREMENTZ & CO., OF SAME PLACE.

DESIGN FOR A LORGNETTE-CASE.

SPECIFICATION forming part of Design No. 29,963, dated January 10, 1899.

Application filed December 17, 1898. Serial No. 699,612. Term of patent 3½ years.

To all whom it may concern:

Be it known that I, HENRY L. GRASMUK, a citizen of the United States, residing at Newark, in the county of Essex and State of New Jersey, have invented and produced a new and original Design for a Lorgnette-Case, of which the following is a specification, reference being had to the drawings accompanying and forming a part of the same.

Figure 1 is a plan view of the outside face of a case for a lorgnette. Fig. 2 is a section on the line *a a* of Fig. 1. Fig. 3 is a section on the line *b b* of Fig. 1.

The general form or outline of the design is a combination of lozenge shapes having free edges and bearing surface decoration of the rococo order combined with a handle of pillar formation of convex profile.

Referring to the drawings, A represents the lozenge-shaped body of the article, around which runs a wide border B of rococo design,

which border surrounds and includes a shield C. At the top of the body is located the crown D, joining the body by a neck of rococo outline. The border B merges into the bust E, bearing the mask F. This bust continues into the fluted and beaded shank of the handle G, which shank is of rounded form. The terminal H is of curved lozenge shape and bears a full face decoration of rococo style. 25

The essential features of the design are the outline form of the body, its handle, and the terminal thereof, including the prominent face decorations. 30

What is claimed as new is—

The design for the case of a lorgnette, substantially as shown and described. 35

HENRY L. GRASMUK.
